(57) **CLAIM**

The ornamental design for a LED string light for aquarium, as shown and described.

DESCRIPTION

FIG. 1 is a perspective view of a LED string light for aquarium showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top view thereof; and,

FIG. 7 is a bottom view thereof.

The dash dash broken line showing of the LED lights is for environmental purposes only and forms no part of the claimed design.

The dash dot dash break lines has been applied along the length to the light to show indeterminate length, with the understanding that the undisclosed portions of the light not shown in the drawings forms no part of the claim design. Patentability is based only on those portions of the article that are shown in solid lines.
